UNITED STATES PATENT OFFICE.

CHARLES DE YOOS, OF NEW YORK, N. Y.

DESIGN FOR A SAVINGS-BANK AND STAND.

44,625.

Specification for Design.

Patented Sept. 2, 1913.

Application filed May 26, 1913. Serial No. 770,078. Term of patent 7 years.

To all whom it may concern:

Be it known that I, CHARLES DE YOOS, a citizen of the United States, residing in the city of New York, borough of Brooklyn, in the county of Kings and State of New York, have invented a new, original, and ornamental Design for a Savings-Bank and Stand, of which the following is a specification, reference being had to the accompanying drawing, forming part thereof.

The figure is a perspective view of a savings bank and stand, showing my new design.

I claim:

The ornamental design for a savings bank and stand, as shown.

CHARLES DE YOOS.

Witnesses:

JOHN E. BURCH,
PHILIP D. ROLLHAUS.
